Primary Examiner — T. Chase Nelson*Assistant Examiner* — Michelle E Wilson*(74) Attorney, Agent, or Firm* — Andrew A Paul(57) **CLAIM**

The ornamental design for an absorbent article with a pattern, as shown and described.

DESCRIPTION

FIG. 1 is an enlarged, partial development view of the claimed left portion of an absorbent article with a pattern seen in its entirety in FIG. 3;

FIG. 2 is an enlarged, partial development view of the claimed right portion of an absorbent article with a pattern seen in its entirety in FIG. 3; and,

FIG. 3 is a development view of the absorbent article with a pattern.

The broken lines, including those showing the diaper tabs and ears, are included for the purpose of illustrating environment and form no part of the claimed design.

The claimed design comprises an ornamental surface pattern printed on flat surfaces in the same plane.
